his Attorney

UNITED STATES PATENT OFFICE.

CYRUS HANKINS, OF BALTIMORE, MARYLAND, ASSIGNOR, BY MESNE ASSIGNMENTS,
TO THE SYMINGTON COMPANY, A CORPORATION OF MARYLAND.

SIDE FRAME.

Application filed September 4, 1923. Serial No. 660,850.

My invention relates to side frames for car trucks, and has been primarily designed to provide a construction which is both strong and stiff but comparatively light in weight, and in which failure of the frame at the critical points therein is reduced to a minimum.

The invention, generally stated, resides in the production of a wrought metal side frame composed of complementary sheet metal wall sections arranged adjacent each other and united to form a very stiff and reliable construction, each of said wall sections involving a plurality of top arch bar portions, bottom arch bar portions and truck column portions.

Particularly stated, one of the principal features of the invention resides in the provision of a wrought metal side frame formed of a plurality of sheet metal blanks, each of said blanks being provided with a relatively small bolster opening and a correspondingly deep beam or truss member integrally uniting the truck columns beneath said opening, said beam member being provided with means adapted to support the bolster springs from points below the bolster opening and upon each side of the longitudinal center of the side frame.

Another object of the invention is to provide a car truck side frame from wrought metal blanks each of which is formed with a plurality of side frame portions having outwardly extending flanges, some of said flanges being designed to support symmetrically located bolster springs from the lowermost portion of the side frame, and the other of said flanges being arranged to form bolster guides, said construction acting to stabilize the opposed side frames of the truck and maintain them in vertical position, said construction also permitting the cross tie member connecting the side frames to be eliminated.

The invention has for a further object the production of a reliable wrought metal side frame having inner and outer side walls each of which is formed with a bolster opening and a plurality of top arch bar portions, bottom arch bar portions, and truck column portions, said truck column portions being integrally united beneath the bolster opening by a very deep beam or truss member of correspondingly increased strength value but of relatively reduced length, said reduc-

tion in length of the beam member being rendered possible by reason of the seating of the bolster springs adjacent the bottom thereof, and serving to materially reduce the stress developed in the side frame at the critical points.

Another feature of the invention involves the production of a side frame from sheet metal blanks each of which is formed with an outwardly projecting flange which extends along the bottom of the side frame, the intermediate portion of each flange being designed to provide a seating surface for the bolster springs, and the respective ends of the flange being designed to overlie the journal boxes of the side frame.

A further object of the invention consists in constructing a car truck side frame of sheet metal walls arranged back to back and firmly united to provide a central longitudinal web, said walls being provided with correspondingly formed portions adapted to receive one end of a pedestal tie bar, said bar being movably positioned between the walls and within said portions for facilitating rapid and convenient application and removal of the journal boxes.

A still further feature of the invention is to provide a side frame construction in which a plurality of sheet metal walls are united with the web of one wall adjacent the web of another wall, each of said walls being formed with symmetrical portions designed to coact to provide recesses or housings for the journal box bolts, said recesses being shaped to engage the heads of the bolts and prevent their rotation. This construction, together with the mounting of the pedestal tie bars, provides a very strong and reliable means for connecting the journal boxes to the side frame as well as permitting convenient assembling and removal thereof.

There are other features of the invention pertaining to the particular relation of the several parts and details of construction, as will hereinafter appear.

In the drawings illustrating the invention, the scope whereof is pointed out in the claims,—

Figure 1 is a view in side elevation of a car truck side frame constructed in accordance with my present invention.

Figure 2 is a detail horizontal sectional view on the line 2—2 of Fig. 1.

Figure 3 is a vertical transverse section on the line 3—3 of Fig. 1.

Figure 4 is a detail plan view of one end of the side frame.

5 Figure 5 is a detail horizontal sectional view on the line 5—5 of Fig. 1.

6 Figure 6 is a similar view on the line 6—6 of Fig. 1.

10 Referring to the drawings, in which similar reference characters designate corresponding parts in the several views, the side frame comprises complementary sheet metal walls or sections 1 and 2, the former constituting the outer wall and the latter the inner wall of the side frame. The walls of the side frame are formed from symmetrical sheet metal blanks each being provided with a bolster opening and having a plurality of 15 top arch bar portions 3, bottom arch bar portions 4, and truck column portions 5. Each sheet metal blank after being cut is then flanged, said flanges being adapted to project outwardly from the web portions of the blanks which latter are abutted and 20 united by a series of rivets 6 advantageously arranged throughout the side frame, although it will be understood that a welding operation may be equally advantageously used to effect the rigid union of the blanks, 25 or portions thereof, so as to produce a single centrally located longitudinal web section of great strength value. Suitable windows 7 are provided in the side frame as the result of the formation of the side frame portions which produce the compression member, tension member, and truck columns, said members and columns being preferably bordered by stiffening flanges 8.

30 The lower edge of the top arch bar portions above the bolster opening are provided with flanges 9, said flanges being continued downwardly adjacent the truck columns, as indicated at 10, and across the lower edge of the bolster opening as designated by the numeral 11. The vertical flanged portions 35 of the truck columns are continued and bent longitudinally of the side frame in spaced relation to the web portion, said bent portions of the flanges 10 providing relatively wide and effective bearing surfaces 12 with which the bolster guides co-operate, 40 said bearing surfaces extending substantially the full height of the bolster opening.

45 The upper edge of each side wall is reinforced by a stiffening flange, said flange having a horizontally disposed portion 13 and an adjacent depending portion 14. Some of the rivets 6 are adapted to unite 50 the side walls along the upper edge thereof in close proximity to the flange portions 13 and 14.

55 The lowermost edge of each side wall is provided with an outwardly projecting flange 15, said flange bordering the bottom arch bar portions as at 16 and being con-

tinued to overlie the journal boxes as indicated at 17. The intermediate portion of each flange 15 is extended beyond the adjacent portions thereof a distance sufficient to 60 form spring seats 18, said seats being designed to receive the bolster springs 19 shown in dotted lines. The outer edge of the spring seat portion of the flange 15 is preferably bent to form a spring retaining wall 20, 65 said wall being suitably curved about the springs and merged into the flange portions 16 stiffening the lower edges of the bottom arch bar portions. The bent edge portions 20 of the flanges are preferably merged into the flanges 16 of the bottom arch bar portions in vertical planes, said portions, in addition to retaining the springs, also serving to materially strengthen the spring seats. 70 Bosses 21 are provided on the spring seat portions, said bosses acting to position the springs whereby they are evenly spaced from the opposite sides of the central web of the side frame and from each other. As a result of the foregoing construction the 75 loads are uniformly imparted to the side frame upon each side of the central vertical web thereof. The mounting of the bolster springs in pockets formed between the inner and outer walls of the side frame and their 80 associated retaining walls, respectively, assures the equal distribution of the loads to the side frame, the action of said springs between the lowermost portions of the side frame and the bolster serving to constantly 85 maintain the side frames in an upright position whereby tipping or canting of the frames as the result of service conditions is 90 prevented.

95 The pedestal tie bars of the truck are indicated by the numeral 22, said bars being 100 pivotally connected at their inner ends to the bottom arch bar portions of the side walls by means of the rivets 23, and having their outer ends arranged to extend beneath 105 the journal boxes. The outer ends of the tie bars are preferably flat and lie in a horizontal plane, the inner ends of said bars being 110 twisted into a vertical plane corresponding to that of the central web portion 115 of the side frame between the opposite walls of which web the inner ends of the respective tie bars are preferably connected.

120 The inner end of each tie bar is received in a recess or housing 24 formed by co-operating depressions provided in the inner abutted faces of the side walls, each of said 125 depressions being of a depth to permit of the recess receiving the pedestal tie bar with sufficient clearance to ensure the pivotal action of the tie bar about the rivet 23 uniting said walls.

130 The pedestal tie bar provides a strong connection between the side frame and journal box, it being noted that said bar can be easily swung down and the journal box

readily placed in position or removed. It will also be observed that the rivet 23, which is supported in both walls, is subjected to double shear, which stress it is particularly well adapted to resist. The extreme inner ends of the pedestal tie bars are shown as preferably curved and designed to engage correspondingly curved bearing faces provided on the interior of the recess 24, said construction tending to increase the rigidity of the tie bar connection.

The journal box bolts (shown in dotted lines) are adapted to be received in recesses 25, said recesses being formed by depressions 15 provided in the inner faces of the side walls, said depressions being shaped to correspond to the side faces of the bolt heads whereby they are prevented from turning. A portion of the shank of each bolt adjacent the 20 head thereof is also encircled by a portion of the metal of each side wall said metal acting in the nature of a column 26 beneath the bolt head and also serving to centrally locate the bolts along the longitudinal center of 25 the side frame.

A side frame constructed in accordance with my present invention can be economically manufactured, the spring seats adjacent the lower opposite edges of the beam or 30 truss member being preferably integrally connected to the web and permitting of a reduction in length of the beam with a correspondingly less stress developed in this portion of the side frame. It will be noted 35 that the height of the web beneath the bolster opening is less than the height of the bolster springs when compressed solid between the spring supporters and the bolster, and also that the intersection of this web 40 portion with the truck columns is along their vertical axis lying between the symmetrically arranged bolster springs.

It will be observed that a very rigid construction of side frame is produced as the result of the central and longitudinal disposition of the abutted walls of the blanks comprising the side frame and the central longitudinal location of the journal box bolts between said walls. My present construction of truck frame not only has the merit of being constructed of light and reliable wrought metal, but its parts are so formed and constructed that the points subjected to greatest strain under service conditions are rendered exceedingly strong.

I claim:—

1. A car truck side frame involving a plurality of metal sheets united to form inner and outer side walls, each of said walls being provided with a bolster opening and having a plurality of truck column portions and bottom arch bar portions, said bottom arch bar portions being connected to the lower ends of the truck column portions and providing a beam member beneath the bolster

opening, and flanges provided on the beam portion of said bottom arch bars, said flanges projecting from the walls of the side frame to form spring supports below the bolster opening. 70

2. A car truck side frame involving a plurality of metal sheets united to form an inner wall and an outer wall, each of said walls being provided with a bolster opening and having a plurality of truck column portions and bottom arch bar portions, said bottom arch bar portions providing a beam member uniting the truck columns at the bottom of the bolster opening, and means projecting from said beam member adjacent each wall of the side frame, said means being adapted to form seats for the bolster springs at points beneath the bolster opening. 75 80

3. A car truck side frame composed of sheet metal walls each of said walls having a bolster opening of relatively shallow depth, and a beam portion arranged beneath the bolster opening, said beam portion being increased in depth corresponding to the reduction in the depth of the bolster opening and having means projecting therefrom adapted to provide seat portions for bolster springs. 85 90 95

4. A car truck side frame involving oppositely arranged separate metal sheets united in abutted relation to form a longitudinally extending centrally located web, flanges provided on said metal sheets disposed at the bottom of the side frame, said flanges having portions providing spring seats upon opposite sides of said web. 100

5. A car truck side frame involving a longitudinally extending and centrally located web having an outwardly projecting flange near the bottom thereof adapted to form a support for the bolster spring at a point in close proximity to the bottom of the side frame, said flange being formed with means thereon for preventing spring shifting. 105 110

6. A car truck side frame comprising complementary flanged metal sheets united to provide inner and outer side walls, each of said walls having a bolster opening and a beam portion beneath said opening, each of said beam portions having a relatively large spring seating area constituting a continuation of the flanged portions of said sheets. 115 120

7. A car truck side frame composed of sheet metal blanks providing inner and outer walls, said walls being connected to form a longitudinally disposed web, stiffening flanges bordering the bottom edge portions of said walls, said flanges having spring seating portions formed integral therewith and disposed upon opposite sides of said longitudinal web. 125

8. A car truck side frame having an inner

wall and an outer wall, said walls being connected to form a longitudinal web, and flanges bordering the lower edge portions of said walls, said flanges having relatively enlarged portions forming spring seating areas upon opposite sides of the web.

9. A car truck side frame having an inner wall and an outer wall, said walls being connected to form a longitudinal web, and flanges bordering the lower edges of said walls, portions of said flanges providing seating surfaces for symmetrically disposed springs upon each side of said web.

10. A car truck side frame having an inner wall and an outer wall, said walls being connected to form a longitudinal web, and flanges bordering the lower edges of said walls, portions of said flanges providing seating surfaces for symmetrically disposed springs upon each side of said web, and other portions of said flanges adjacent the seating surfaces being bent to form retaining means for said springs.

11. A car truck side frame having an inner wall and an outer wall, said walls being connected to form a longitudinal web, and flanges bordering the lower edges of said walls, portions of said flanges providing horizontally disposed seating surfaces for symmetrically arranged springs upon each side of the web, and other portions of said flanges being vertically disposed adjacent the seating surfaces.

12. A car truck side frame having an inner wall and an outer wall, said walls being connected to form a longitudinal web, and flanges bordering the lower edges of said walls, portions of said flanges providing seating surfaces for symmetrically disposed springs upon each side of the web, and other portions of said flanges being adapted to border said seating surfaces for retaining the springs in their symmetrical relation.

13. A car truck side frame having an inner wall and an outer wall, said walls being connected to form a longitudinal web, flanges bordering the lower edges of said walls adapted to provide seating surfaces for symmetrically disposed springs upon each side of said web, and means provided on said flanges for centering the symmetrically positioned springs.

14. A car truck side frame having an inner wall and an outer wall, said walls being connected to form a longitudinally disposed web provided with a bolster opening of relative shallow depth, said web extending beneath the bolster opening to provide a beam member the depth of which is increased corresponding to the reduction in depth of the bolster opening, and means extending from said web upon opposite sides thereof for supporting bolster springs from a point below the bolster opening, the height of the web beneath said opening being less

than the height of the bolster springs when they are compressed solidly between said supporting means and the bolster.

15. A car truck side frame having an inner wall and an outer wall united to provide a longitudinally extending web, each of said walls having a plurality of top arch bar portions, a plurality of bottom arch bar portions, and a plurality of truck column portions; and pedestal tie bars connected to said web, said pedestal tie bars having their outer ends disposed to project beneath the journal boxes and their inner ends arranged between said inner and outer walls.

16. A car truck side frame involving oppositely arranged metal sheets providing inner and outer side walls, said metal sheets being disposed with the inner face of one wall adjacent the inner opposed face of the other wall, and pedestal tie bars having their inner ends movably connected to the side frame between the inner and outer walls.

17. A car truck side frame comprising a plurality of metal sheets arranged to form inner and outer walls, each of said walls having a plurality of top arch bar portions, a plurality of bottom arch bar portions, and a plurality of truck column portions; and pedestal tie bars movably mounted between said inner and outer walls at the junction of the truck column portions with the bottom arch bar portions.

18. A car truck side frame comprising a plurality of metal sheets disposed adjacent one another and in abutted relation, each of said sheets having a portion adapted to coact with a corresponding portion of the adjacent sheet to form a recess, and a pedestal tie bar movably mounted in said recess.

19. A car truck side frame comprising a plurality of metal sheets disposed adjacent one another and in abutted relation, each of said sheets having a portion adapted to coact with a corresponding portion of the adjacent sheet to form a recess, a pedestal tie bar of less width than that of said recess, and means including a transverse member pivotally connecting the tie bar within the recess for free swinging movement, said means also serving to unite the metal sheets.

20. A car truck side frame composed of complementary metal sheets united to provide inner and outer walls, each of said walls being provided with recessed portions adapted to coact with similar portions on the adjacent wall to provide journal box bolt openings, each of said recessed portions being shaped to contact the head of the journal box bolt for preventing its rotation.

21. A car truck side frame having an inner wall and an outer wall, each of said walls being provided with portions adapted to engage the side of the head of a journal box bolt, said walls being spaced adjacent

said engaging portions to provide journal box bolt openings located between said inner and outer walls.

22. A car truck side frame composed of sheet metal inner and outer walls, each of said walls being recessed on their opposed inner faces to provide journal box bolt openings, portions of said walls adjacent the openings being shaped to engage the bolt heads and other portions of said walls being disposed to provide columns beneath said bolt heads.

23. A car truck side frame composed of sheet metal inner and outer walls, each of said walls being formed with corresponding side frame portions and united to provide a longitudinally extending centrally located web, stiffening flanges disposed at the upper edges of said walls, said flanges having depending edge portions arranged in vertical and parallel relation to said web upon opposite sides thereof, and means uniting said inner and outer walls adjacent said flanges.

24. A car truck side frame involving metal sheets united to form inner and outer walls of a side frame of standard A. R. A. dimensions, each of said walls having a bolster opening of relative reduced depth, a plurality of top arch bar portions, a plurality of bottom arch bar portions, a plurality of truck column portions, said bottom arch bar portions being disposed to provide a beam member of relative increased depth corresponding to the reduction in depth of the bolster opening, said beam member being correspondingly reduced in length for minimizing the stresses developed at the critical points of the side frame adjacent the junctions of the truck column portions with the bottom arch bar portions.

25. A car truck side frame comprising sheet metal symmetrically formed members united to provide a longitudinally disposed web, each of said members having a plurality of top arch bar portions, a plurality of bottom arch bar portions, and a plurality of truck column portions, and stiffening flanges on said truck column portions, the outer edges of said flanges being disposed in parallel relation to said web and providing bolster guides.

26. The combination with a railway car truck of a side frame involving inner and outer walls united to provide a web disposed longitudinally of the side frame, each of said walls having a bolster opening of

comparatively shallow depth and a beam portion beneath said opening of increased depth, means projecting from each side wall beneath the bolster opening, said means being adapted to form symmetrical spring supports upon each side of the longitudinally disposed web, symmetrically arranged springs, and a bolster resting on said springs, the reaction of said bolster upon the side frame through said springs serving to maintain the side frame in a vertical plane with respect to the bolster.

27. The combination with a railway car truck of a side frame having inner and outer walls united to provide a web disposed longitudinally of the side frame, each of said walls having a bolster opening, a plurality of top arch bar portions, a plurality of bottom arch bar portions, and a plurality of truck column portions; flanges provided on said truck column portions adapted to form bolster guides disposed in parallel relation to said web, flanges provided on said bottom arch bar portions and projecting laterally upon each side of the web to form spring seats near the bottom of the side frame, symmetrically arranged springs, and a bolster, the reaction of the bolster upon the side frame through the symmetrically arranged springs acting to maintain the frame in vertical position.

28. A car truck side frame involving a compression member, a bottom tension member and truck columns, said bottom tension member being provided with spring seats projecting outwardly from each side of the lower edge portion thereof, and formed with means thereon adapted to prevent spring shifting, the neutral axis of the bottom tension member and the truck columns intersecting longitudinally of the side frame at points between said spring seats.

29. A car truck side frame composed of complementary metal sheets united to provide inner and outer walls forming a longitudinally extending web, each of said sheets having portions adapted to coact with corresponding portions on the adjacent sheet to form journal box bolt openings, said openings being shaped to surround the bolt heads and disposed in alignment with the longitudinally extending web.

In testimony whereof I affix my signature.

CYRUS HANKINS.
